METHOD AND APPARATUS FOR MAKING
BLANKS FROM CANS

Darrell A. Froom, Santa Maria, Calif.

Application July 6, 1943, Serial No. 493,642

8 Claims. (Cl. 164—10.6)

This invention relates to a method and apparatus for making flat blanks from cans.

The general object of the invention is to provide both a novel method and apparatus by means of which a flat blank may be made from an ordinary tin can. Flat blanks of this nature are useful since various articles such as bottle caps, toys, etc. may be made from them and thus valuable material may be salvaged.

A more specific object of the invention is to provide a novel apparatus for cutting the ends from a tin can.

A further object of my invention is to provide a novel cutting means for severing the ends from a tin can to provide a flat blank.

A further object of the invention is to provide a novel fixed cutting member assembly which is particularly adapted for use in a blank making apparatus.

Another object of the invention is to provide a novel removable cutting member assembly which is particularly adapted for use in a blank making apparatus.

A further object of the invention is to provide a novel means for driving the feed rolls and cutter of a blank making apparatus.

Other objects and the advantages of my invention will be apparent from the following description taken in connection with the accompanying drawings wherein:

Fig. 1 is a top plan view with parts broken away showing my apparatus;

Fig. 2 is a side elevation with parts in section showing my invention;

Fig. 3 is a section taken on line 3—3, Fig. 1;

Fig. 4 is a section taken on line 4—4, Fig. 1;

Fig. 5 is a section taken on line 5—5, Fig. 2;

Fig. 6 is an end view with parts in section showing the cutting members;

Fig. 7 is a section taken on line 7—7, Fig. 4, and

Fig. 8 is a plan view showing a can prepared for feeding to my apparatus.

Referring to the drawings by reference characters, I have shown my invention as embodied in an apparatus for making blanks from tin cans which is indicated generally at 10.

As shown the apparatus includes a base 11 having a pair of spaced vertical standards 12 arranged thereon. The standards include outwardly directed flanges 13 at the top, bottom and sides, with the flanges at the bottom held on the base 11 by bolts 14.

The standards 12 are spaced apart by a pair of upper rods 15 and a lower rod 16. The rods

15 and 16 have reduced threaded ends which receive nuts 17 and 18 respectively.

On the inside of each of the standards 12 I provide a portion 21 which serves as a support member for the cutter assembly. The portions 21 have inclined plane upper faces 22. My cutter assembly, which is indicated generally at 23, includes a transverse base or table member 24. This member 24 has depending flanges 25 at each end thereof. The flanges 25 are aligned with the portions 21 and the lower faces of the flanges are plane and engage the faces 22 on the portions 21. Bolts 26 and 27 pass through the flanges 25 and also through the flanges 12 to hold the cutter assembly in place. When the bolts 26 and 27 are removed the cutter assembly may be removed to permit sharpening of the shear members (to be later described) or for substitution of other shear members.

The transverse member 24 has a flat, upper intermediate, substantially horizontal, surface 28 and the forward end of this transverse member turns downwardly as at 29. The cans, as shown in dotted lines at 30, Fig. 4, being operated upon pass over this curved surface 29 and onto the surface 28 and rest upon lower shear members 31.

The shear members 31 consist of flat hardened blades each being bevelled as at 32 and having a relief recess 33 (see Fig. 7). The shear members engage portions 34 in flanges 35 arranged on the transverse member between the flanges 25. The members 31 are held in place by screws 36.

The flanges 35 are provided with aligned apertures 37 through which an elongated rod 38 extends. This rod 38 is provided with threaded extremities which receive nuts 39 to hold the rod in place. Pivoted upon this rod 38 at each end thereof and just outside of the shear blades 31 I arrange pivoted shear members 40. Each of these shear members 40 consists of a body 41 having a slot 42 in the upper portion thereof.

The walls defining the slot 42 are provided with aligned apertures 43 and a rod 44 passes through all these apertures and is held in place by nuts 45. The rod 44 is shown as provided with bearings 46 which support cam rollers 47. Mounted upon the rod 44 I show a spring support member 48 which has a tongue 49 (Fig. 4) engaging the body 41. A tension spring 50 engages the member 48 at one end while the other end of the spring engages one of the rods 15 previously described. The springs 50 tend to raise the members 41 to elevated position.

Each of the members 41 is provided with a rabbet 51 which has a straight upper face 52. In this rabbet I arrange a cutting blade 53. These cutting blades 53 have straight upper faces 54 which engage the upper face 52 of the rabbets 51. Each blade 53 is bevelled as at 56 and has a relief recess 57 therein and is removably held in place by screws 58 so that it may be readily removed for sharpening or repair.

The standards 12 are provided with slots 59 at each end through which cylindrical end portions 60 on a cam shaft 61 extend. The cam shaft 61 is supported by suitable bearings 62 (Fig. 5) and at the left end in Fig. 1 the cam shaft receives a V-pulley 63 which is held in place as by a set screw 64. The pulley is adapted to be driven by a V-belt 65 from a pulley 66 on a shaft 67 which is adapted to be driven by a motor 68.

The cam shaft 61 includes a cam surface 69 which engages the rollers 47 on the shiftable cutting members and the construction is such that as the motor operates and the cam shaft is rotated the cam shaft will periodically depress the rollers, thus moving the movable cutting members towards the fixed blades, after which as the cam rotates the springs 50 will lift the movable cutting members 40 after the cut is made.

At the left in Fig. 1 I show a can guide indicated generally at 70 which comprises a bar 71 having apertures receiving the adjacent bolts 26 and 27 so it is held in place. The bar 71 has apertures 72 (Fig. 1) through which threaded pins 73 on a guide plate 74 extend. Nuts 75 serve to hold the guide plate 74 in position. The guide plate is arranged outside of the adjacent cutting members and is adapted to be engaged by the end of a can being operated on to correctly position the can. A cover 76 engages the pins 73 and has an inturned lower end 77 which resiliently clamps it to the pins 73. The member 76 acts to space the guide plate 74 from the supporting bar 71. The width of the member 76 determines the location of the guide plate and the latter determines the width of the blank which is being cut. There is only one guide plate 74 which is located, as shown in Fig. 1, at the left side of the apparatus and adjacent to one cutting member.

In operating my apparatus the can is usually provided with a double slit (as later described) but with some cans only a single slit is necessary. The can is moved by hand so that the parts 29 and 31 enter the can and then the can is rotated by hand until it is engaged by a pair of rolls 80 and 81 which advance the can. The upper roll 80 is supported in bearings 82, arranged in a block 83 which slides in ways 84. The ways 84 are arranged in plates 85 held on the standards 12 by bolts 86. The blocks 83 are held in adjusted position by bolts 87 which threadedly engage the plate 85 and abut the tops of said blocks.

The lower driven roll 81 is mounted in sliding blocks 88 which engage the ways 84. The blocks 88 engage resilient cushion members 89 (Fig. 3) which in turn engage the bottom wall 90 of the ways. The cushion members 89 have sufficient resiliency to allow the rolls to separate, as indicated at 91, the necessary amount to frictionally engage the lower surface of the roll which advances the uncut portion of the can towards the cutting members.

The roll 80 is driven from the roll 81 by gears 92 and 93 which are arranged upon the ends of the roll members at one end of the apparatus. At the other end the driven roll 81 is provided with a housing 100 which is free to turn thereon.

This member 100 has a fixed crank arm 101 thereon which is connected to a pitman 102 by a pin 103. The pitman 102 remote from the pin 103 has a head member 104 within which I arrange a suitable bearing 104' which receives a crank arm 105 mounted on a disc member 106 which is held on the cam shaft 61 by a set screw 107.

The construction is such that as the cam shaft 10 rotates the pitman 102 will first advance the member 100 and then will retract this member. The member 100 is connected to the feed roll shaft 108 by a ratchet type member 109. This ratchet includes a tooth member 110 keyed to one end of the roll 81 by a key 111 (Fig. 3). The ratchet details form no part of the present invention and a further description of this member is believed unnecessary.

A nut 112 threadedly engages the end of the feed roll shaft 108 to retain the ratchet unit in place.

Adjacent the feed rolls 80 and 81 and having its upper surface slightly above the center between the feed rolls, I provide a straightening roll 113 which is secured in blocks 114 held in ways 115 in the plates 85. This roller 113 serves to engage the cut blank, shown by dotted lines at 116, as it leaves the rolls 80 and 81 and to straighten it into a flat blank. The blocks 114 are held in adjustable position by screws 117 (Fig. 2) which threadedly engage the plates 85 and abut said blocks.

In Fig. 8 I show the can 30, having ends 30a and having a longitudinal seam 30b. The can 30 before being operated upon by my apparatus is slotted as at 30c along one side of the seam. I have found that the double slitting is usually preferable as it is then not necessary to cut through the middle seam 30b. With some cans, however, and under some conditions it may be desirable to make merely the single cut 30d before the can is fed to my apparatus.

From the foregoing description it will be apparent that I have invented a novel machine for making blanks from cans which is rapid in operation, easily manufactured and not likely to get out of order.

Having thus described my invention, I claim:

1. In an apparatus for making blanks from tin cans, a pair of spaced cutting members, means to pivotally support said cutting members a feed roll in advance of said cutting members, the axis of said feed roll being parallel to the axis of the pivotal support of the cutting members, means to operate the cutting members, and means operated by the cutting member operating means for driving the feed roll.

2. In an apparatus for making blanks from tin cans, a table adapted to support an intermediate portion of a can body, a pair of cutting members, one at each end of the table, guide means adjacent to one cutting member, means to operate the cutting members to simultaneously cut off both ends of a can, and means to advance the can step by step towards both cutting members.

3. In an apparatus for making blanks from tin cans, a base, a pair of standards on the base, a table extending between said standards, a pair of flanges mounted on the table intermediate the ends thereof, a cutting member support on said flanges and a cutting member assembly on said cutting member support.

4. In an apparatus for making blanks from tin cans, a pair of spaced, coaxially mounted pivoted cutting members, a fixed shear plate adjacent to

each cutting member, a feed roll in advance of said cutting members, the axis of said feed roll being parallel to the axis of the cutting members, a cam roller on each cutting member, a cam rod having cam surfaces engaging the cutting member cam rollers to actuate the cutting members to cutting position, means to drive the cam rod and means operated by the cam rod to drive the feed roll.

5. In an apparatus for making blanks from tin cans, a support member having a plane upper face, a cutting member assembly having a plane lower face engaging the plane face on the support, means to hold the assembly in place, said assembly including a body having a blade support thereon, and a blade engaging the blade support, said blade being relieved on its cutting face.

6. In an apparatus for making blanks from tin cans, a table, a pair of flanges mounted on the table, a cutting member support mounted on said flanges, a movable cutting member assembly mounted on said support, said assembly including a body having a cam roller thereon, a blade carried by said body, a cam and means whereby said cam engages said roller to move the cutting member body.

7. In an apparatus for making blanks from tin

cans, a base, a pair of spaced standards on the base, a support member on each standard, each support member having a plane upper face, a pivoted cutting member assembly mounted on each base, each assembly having a portion including a plane lower face engaging the plane face on the support, means to hold each assembly in place, each assembly including a body having a cam roller thereon, a blade support on the body, a blade engaging the blade support, said blade being relieved on its cutting face.

8. In an apparatus for making a blank from a tin can, a support for a can body, a cutting member at each end of the support for severing the ends of a can body, a pair of feed rolls in advance of the cutting members, means to adjustably support said feed rolls, resilient means engaging one of said feed rolls, means to drive the cutting members, said means including a cam shaft, a crank member mounted on the cam shaft, a pitman on the crank member, a housing on said feed roll, ratchet means connecting the housing and said feed roll, said housing having an arm thereon and means pivotally connecting the arm and the pitman.

DARRELL A. FROOM.
